UNITED STATES PATENT OFFICE.

COLIN MCORIE AND DANIEL JEFFERSON HUNTER, OF COUNTY OF SURREY,
ENGLAND.

TOOL FOR CUTTING METAL.

SPECIFICATION forming part of Letters Patent No. 705,695, dated July 29, 1902.

Application filed February 27, 1902, Serial No. 96,001. (No model.)

To all whom it may concern:

Be it known that we, COLIN MCORIE and DANIEL JEFFERSON HUNTER, engineers, subjects of the King of Great Britain, residing at 5 97 Camberwell New Road, in the county of Surrey, England, have invented certain new and useful Improvements in Tools for Cutting Metal, of which the following is a specification.

This invention relates to improvements in 10 tools for cutting cylindrical lengths of metal, such tools being especially applicable to cutting blanks in which extreme accuracy is required, such as for micrometer-screw blanks.

According to this invention each cutter is 15 a segment of a metal ring, (a small segment only having been cut away from the ring,) the front or working end of which has an outer surface lying in a plane at right angles to the axis of the cutter. A portion of one of 20 the radial edges of the segment nearest to the central hole forms a cutting edge. The other radial edge is not in the same plane with it; but the face of the disk is recessed, the recess slowly deepening, so that the bottom of 25 the recess forms a slow spiral. The extent of this recess determines the amount the work will be fed forward at each revolution. The cutter is clamped and held fast in the interior of a tubular holder. One end of the tube 30 which forms the holder has an inwardly-projecting flange. The other end has a screw-thread cut upon it. A portion of the side of the tube is cut away to allow the shavings cut off by the cutter or cutters to pass away. 35 A small flanged ring is placed within the flanged end of the tubular holder, the flange on the ring bearing against the inner face of the flange of the holder. The hole through this small ring is of the same diameter as the 40 end of the metal rod which is to be shaped and serves to hold it concentric with the tubular holder. Next to the small ring is placed a cutter. By exchanging one sized cutter for another or by the use of a greater or less number of distance-pieces metal rods of different 45 diameters or lengths or cut with a square or round shoulder may be made, the change being effected with great ease.

In order that our invention may be better 50 understood and readily carried into effect we

will describe it with reference to the accompanying drawings.

Figure 1 is a side elevation; Fig. 2, a side elevation, partly in section, and Fig. 3 a section of the tool, and Fig. 4 a face view of the 55 same. Fig. 5 is the blank formed by the combination of cutters shown in Fig. 3. Fig. 6 is a front section showing the cutter D, taken on the line A A of Fig. 3. Fig. 7 is a front view, Fig. 8 a side view, and Fig. 9 a section 60 of the same shown to a larger scale. Fig. 10 is a section on the line B B of Fig. 2. Fig. 11 is a perspective view, Fig. 12 a plan and side elevations, taken at right angles to each other, of the cutter G of Fig. 3. Fig. 13 is a front elevation, Fig. 14 a side elevation, Fig. 15 a section, and Fig. 16 a perspective view, of a modified form of cutter.

In the drawings, A is the tubular holder; B, the inwardly-projecting flange on the front 70 end of the same. The rear end of the holder is screw-threaded. If it be required to make a blank shaped as shown in Fig. 5, a flanged ring C is first pushed through the open end of the holder, then a cutter D, a distance-piece E, a second cutter F, a cutter G for cutting the point of the blank, and a plug H, and the whole screwed tight by the screw-plug I. The details of the cutters will be described 75 later.

The tool-holder is held fast in the slide-rest of a lathe while the metal rod to be shaped is rotated, the feed being governed by the spiral recess of the foremost cutter.

It will readily be seen that by the use of 85 more distance-pieces E or cutters and distance-pieces having a larger or smaller bore for the passage of the work, or even the use alone of an end cutter G, a great variety of work can be produced, the cutters being removed and replaced by others with very great 90 ease.

The cutter D consists of a segment having, as shown, a central hole for the passage of the work, the front or working end of the segment having an outer surface lying in a plane at right angles to the axis of the cutter. The portion d of the radial edge is the cutting edge. The other edge d' is not in the same plane with it, but the face of the disk is re- 95 100

cessed, the recess slowly deepening from d to d' , so that the bottom of the recess forms a slow spiral. The extent of the recess at d' may for fine work be one one-hundredth of 5 an inch. The recess determines the feed at each revolution. A cutter such as shown will cut a square-shouldered rod. The second cutter F is similar to the above, but the bore for the passage of the work is smaller, 10 and therefore a stepped blank is produced.

The distance-piece E is a segment of a disk and is shown in Fig. 10.

The cutter G for forming the end is shown in perspective to a larger scale in Fig. 11 and 15 in plan and side elevations taken at right angles to each other in Fig. 12.

g is the cutting edge.

If a conical shoulder be desired, cutters such as shown to a larger scale in Figs. 13, 20 14, 15, and 16 are used.

The cutting-face a is hollowed out at a' to the shape it is intended to form the shoulder. The face is, as before, provided with a spiral recess, (shown most clearly in Fig. 15,) in 25 which a^2 shows the plane of the cutting edge and a^3 the bottom of the recess.

What we claim is—

1. A cutter for cutting cylindrical lengths consisting of a segment of a metal ring, the 30 front or working end of which has an outer surface lying in a plane at right angles to the axis of the cutter, and having also a curved recess the inner surface of which gradually deepens as it extends around the axis, the 35 inner portion of one of the radial edges of the segment forming the cutting edge, while the similar inner portion of the other radial edge is at the inner end of the gradually-deepening recess in rear of the cutting edge.

40 2. The combination of a cutter for cutting cylindrical lengths of metal consisting of a segment of a metal ring the inner portion of one of the radial edges forming the cutting edge while the similar inner portion of the 45 other radial edge is not in the same plane with it a gradually-deepening recess being formed in the face of the segment with a tubular holder one end of which has an inwardly-projecting flange and in which a portion of the side is cut away and means for

holding the cutter stationary within the tubular holder.

3. The combination of two or more cutters for cutting cylindrical lengths of metal each consisting of a segment of a metal ring the 55 inner portion of one of the radial edges forming the cutting edge while the similar inner portion of the other radial edge is not in the same plane with it a gradually-deepening recess being formed in the face of the segment, 60 and a distance-piece inserted between said cutters, with a tubular holder one end of which has an inwardly-projecting flange and in which a portion of the side is cut away and means for holding the cutters stationary 65 within the tubular holder.

4. The combination of a cutter for cutting cylindrical lengths of metal consisting of a segment of a metal ring the inner portion of one of the radial edges forming the cutting 70 edge while the similar inner portion of the other radial edge is not in the same plane with it a gradually-deepening recess being formed in the face of the segment, and a cutter for pointing the end of the metal length, 75 with a tubular holder one end of which has an inwardly-projecting flange and in which a portion of the side is cut away and means for holding the cutters stationary within the 80 tubular holder.

5. The combination of two or more cutters for cutting cylindrical lengths of metal each consisting of a segment of a metal ring the inner portion of one of the radial edges forming the cutting edge while the similar inner 85 portion of the other radial edge is not in the same plane with it a gradually-deepening recess being formed in the face of the segment, a distance-piece inserted between said cutters, and a cutter for pointing the end of the 90 metal length, with a tubular holder one end of which has an inwardly-projecting flange and in which a portion of the side is cut away and means for holding the cutters stationary within the tubular holder.
